United States Patent Office

Des. 193,158
Patented July 3, 1962

193,158

COMBINED PACKAGING AND SERVING CONTAINER

Frank A. Buonauro, 1219 Summit Ave., Union City, N.J.

Filed Mar. 10, 1961, Ser. No. 64,213

Term of patent 14 years

(Cl. D58—25)

FIG. 1.

FIG. 2.

FIG. 3.

FIG. 1 is a perspective view of the combined packaging and serving container showing my new design.

FIG. 2 is an exploded side elevational view thereof.

FIG. 3 is a horizontal cross section taken on the line 3—3 of FIG. 2.

I claim:

The ornamental design for a combined packaging and serving container, as shown.
